(57) **CLAIM**

The ornamental design for a luminaire, as shown and described.

DESCRIPTION

FIG. 1 is a bottom perspective view of a luminaire, showing my new design.

FIG. 2 is bottom plan view thereof; and,

FIG. 3 is a front elevational view thereof.

The left side, right side and rear elevational views are identical to the view in FIG. 3.

The top of the luminaire forms no part of the claimed design.
